UNITED STATES PATENT OFFICE

ALEX J. ENGEL, OF CHICAGO, ILLINOIS

SUPPORTING ARTICLE

Application filed May 11, 1931. Serial No. 536,574.

This invention relates to certain novel improvements in supporting articles, and has for its principal object the provision of an improved construction of this character which will be highly efficient in use and economical in manufacture.

Among the several objects of this invention is to provide a supporting device which may be conveniently attached about the body of the wearer and which includes a simple combination and arrangement of parts for effectively and conveniently attaching and detaching articles to be supported therefrom.

A still further object of the invention is to provide a strap of a supporting article which includes a simple combination and arrangement of parts for conveniently attaching and detaching an article thereto.

A still further object of the invention is to provide a supporting device which includes an inexpensive arrangement for protecting metallic parts of the device from contact with the body.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of the supporting device embodying the invention;

Fig. 2 is a fragmentary sectional detail view of the same taken substantially on the line 2—2 of Fig. 1;

Fig. 3 is a fragmentary perspective view of the connecting means embodied in the invention; and

Fig. 4 is a plan view of the loop element embodied in the invention.

Referring more particularly to the drawings, the several objects of the invention are accomplished by providing a strap 10 which includes a buckle structure 11 of any approved type whereby the strap may be conveniently placed about the body of the wearer.

Extending from this strap 10 are ribbon-like strips 12, these strips 12 being attached

to the strap 10 by means of stitches 13. Inwardly of the lower end portions 14 of these strips 12 the strips are bent upon themselves to provide a transverse beading 15 in which is adapted to be confined the opposite end portions 16 of the loops 17. Each of these loops 17 is preferably formed from a single length of wire bent to provide a constricted slit 18 at its lower end portion, with opposite adjacent portions 19 of the wire member resiliently bowed toward each other as at 20 to provide a wedge or clamp for clamping engagement with the garment 21. The abutting ends of the loop are preferably connected together as at 22 by spot welding or the like.

In use, by reason of the resilient property of each of the loops, the garment 21, when confined within the restricted slit will be effectively clamped or wedged in this slot so as to provide an effective connection between the garment 21 and the strip 12 to which it is attached.

As shown in the drawings, the lower end portion 14 of each of the strips extends beyond the lower end portion of each of the loops. This arrangement is such that the body of the wearer will be protected from contact with the loops 17 thereby avoiding irritation resulting from rubbing and the like.

In practical use it might be found advisable to dispense with the strap 10. When such is the case the strips 12 may be connected to other garments of the wearer by means of safety pins or the like.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Having thus described my invention, what I claim as new and desire to protect by Letters Patent is:

In an article of the character described a

flexible strip including a portion bent upon itself to provide a bead transverse to the axis of the strip, a garment fastening element including a loop having a portion disposed in the bead to swingingly mount the fastening element on the strip, the fastening element including a pair of yieldable garment clamping arms integral with the loop and bowed toward, and normally urged into abutting and garment clamping engagement with, each other, at a point between their ends, said arms including portions bowed apart to provide a restricted opening for the introduction thereinto of a portion of a garment which may then be forced between the arms whereby to force the arms apart at said abutting point and into clamping engagement with said garment portion, and a tab depending from said strip and extending through said loop so as to prevent the clamping portions of said arms from engaging and irritating the flesh of the wearer.

In testimony whereof I affix my signature.
ALEX J. ENGEL.
